UNITED STATES PATENT OFFICE.

JOHN H. CRESMER, OF RIVERSIDE, CALIFORNIA.

FORM FOR CONCRETE CONSTRUCTION.

1,323,020.

Specification of Letters Patent. Patented Nov. 25, 1919.

Application filed September 9, 1918. Serial No. 253,258.

To all whom it may concern:

Be it known that I, JOHN H. CRESMER, a citizen of the United States, residing at Riverside, in the county of Riverside and State 5 of California, have invented new and useful Forms for Concrete Construction, of which the following is a specification.

This invention pertains to forms for casting cement or concrete walls *in situ* and an 10 object of the invention is to effect the construction of cement or concrete walls as expeditiously and inexpensively as possible.

Another object is to make provision for readily casting or pouring a hollow or cham- 15 bered wall.

Another object is to produce a contractive inside form for walls and one that can be readily raised into a new position after a section of the wall has been poured so that 20 another section can be poured to increase the height of the wall being made.

Another object is to produce an inside form that can be expanded and contracted uniformly from end to end so that it can 25 be readily freed from the walls of the hole when it is desired to remove the inner form from the partly set section of the wall.

Another object is to so construct a chambered wall that the chambers thereof will 30 hold water so that the wall can be properly cured.

Other objects and advantages will appear in the subjoined detailed description.

The accompanying drawings illustrate the 35 invention.

Figure 1 is a side elevation of a construction embodying the invention, a portion of a wall being shown already cast and some of the outer form plates being omitted and 40 others partly broken away and some of the wall being shown in vertical mid section for clearness of illustration. One of the inner forms is shown partly in section.

Fig. 2 is an enlarged plan view from line 45 x^2-x^2 , Fig. 1, the inner form operating rod being shown in section on said line.

Fig. 3 is a plan section on line indicated by x^3-x^3 , Fig. 1.

Fig. 4 is a plan section analogous to Fig. 50 3 excepting that the inner form is contracted ready for withdrawing it from the chamber which it has formed in the wall.

Fig. 5 is a vertical mid section on line indicated by x^5-x^5 , Fig. 2.

Fig. 6 is a perspective view of one of the inner forms.

Fig. 7 is a perspective view of the cap of the inner form and its supporting plate.

Fig. 8 is an inverted plan view of the parts shown in Fig. 7.

Fig. 9 is a plan view of the outer form frame.

There are provided standards 1 arranged at the four corners of the wall which is to be constructed, and fastened to the standards 1 65 65 members 2. The standards 1 and members 2 constitute the frame of the outer form. The horizontal members 2 are adapted to hold rectangular outer form plates 3 and for this 70 purpose the upper faces of the horizontal members are provided with longitudinally extending grooves 4 adapted to be engaged by endwise-shiftable latches 5 having slots 6 to accommodate screws 7 which extend 75 into the plates to retain the latches and allow the latches to be raised and lowered so that they can be withdrawn from the grooves 4 and forced into engagement with said grooves. The grooves 4 and latches 5 prevent the lower ends of the plates 3 from shifting in and out. Also the lower faces of the horizontal members 2 are provided with longitudinally extending grooves 8 to receive the upper ends of the plates 3, said 80 grooves preferably having their inner faces beveled inward and downward so as to facilitate removal of the plates when the latches 5 are raised and the lower ends of the plates 85 are swung outward. The upper edges of the plates 3 are beveled inward and downward to 90 suit the bevel of the grooves 8.

The horizontal members 2 are preferably held toward one another by ties 9 in the form of wires or rods, the end portions of the 95 wires 9 passing through horizontal perforations 10 in the horizontal members. The ends of the wires 9 project beyond the outer faces of the horizontal members and pass through perforations 11 in washers 12. The 100 ends of the wires 9 are bent over to form hooks 13 which engage perforations 14 in the washers 12. Wedges 14' are inserted between the washers 12 on one side of the form and the outer faces of the adjacent 105 members 2 so as to draw the wires 9 taut. The wires 9 are arranged at suitable intervals along the horizontal members 2 and sufficient of said wires will be provided to prevent spreading apart of the horizontal 110 members at any point. Thus it is clear that the wires 9 and washers 12 prevent move-

ment away from one another of the horizontal frame members and that said members prevent spreading of the plates 3. The horizontal members 2 are arranged in superposed pairs and may be all constructed alike, though it is obvious that the grooves 4 in the uppermost members are not required and that the grooves 8 in the lowermost members are not used. In practice the lowermost members 2 may be placed directly on the footing or foundation, not shown, on which the wall is to be constructed.

The horizontal members 2 are adapted to form supports for the inner forms which will now be described. Resting on the uppermost pair of horizontal members 2 are plates 15 which are provided with two or more vertical perforations 16 in which may be selectively placed pins 17 that may have their upper ends bent over to form heads 18. The pins 17 also project into vertical perforations 19 in the horizontal members 2, thus to hold the plates 15 in fixed position relative to the horizontal members. Besides this, it is clear that the plates 15 also function to prevent movement toward one another of the horizontal members 2 as well as movement thereof away from one another. By reason of the plurality of holes 16, it is obvious that different thicknesses of wall may be provided for since positioning the pins in different holes will space the opposite horizontal members 2 and plates 3 closer together or farther apart.

The plates 15 are provided with orifices 20 through which are adapted to extend upright sectional stems each formed of a pair of wedge members 21, 22, the outer faces of the wedge members being substantially parallel with one another and the inner faces being complementarily beveled as indicated at 23. When the wedge members 21, 22 are somewhat offset from one another, as clearly shown in Fig. 3, each pair exactly fits the orifice 20, since the orifices include laterally projecting recesses 24 into which the projecting edges of the wedge members 21, 22 extend. Owing to the orifices 20 accurately fitting the wedge members 21, 22, when the wedge members are offset from one another, it is clear that the plates 15 serve to lock the wedge members in their offset positions. When the wedge members 21, 22 are offset from one another, that is when they are slid upon one another at their faces 23, the wedge members 21, 22 are in their form-expanding positions, and in such positions the outer oppositely arranged faces of the wedge members are farther apart than when the wedge members are moved into registration with one another, as in Fig. 4, this latter position being the form-contracting position of the wedges.

Suitable means are provided to move the wedge members 21, 22 into form-expanding

and form-contracting positions and for this purpose the wedge members are provided in their opposed faces with longitudinal grooves 24' adapted to receive operating rods 25, there being one rod for each pair of wedge members 21, 22. The rods 25 are sufficiently wide so that when they are turned about their longitudinal axes they exert leverage on the wedge members 21, 22 to slide said wedge members into expanded or contracted positions according as the rods 25 are turned clockwise or counter-clockwise in Figs. 2, 3 and 4. Preferably the upper ends of the rods 25, for convenience in operating them, are bent at right angles to form horizontally extending handles 26 whereby greater leverage may be applied by the operator to turn the rods 25.

As stated above the plates 15 lock the upper portions of the wedge members 21, 22 in their expanded positions and means are also provided to lock the lower portions of the wedge members 21, 22 in expanded positions and these means will now be described. Suitably fastened to each of the wedge members 21 is an ear 27 which extends past the joint between the wedge members. When the wedge members 21, 22 are in their expanded positions the ear 27 is spaced from the adjacent face of the wedge member 22 so as to accommodate a locking wedge 28 which is operated by a rod 29 passing through cleats 30 at intervals along the wedge member 22. The operating rods 29 extend upwardly sufficiently far so that they can readily be reached by the operator for operation thereof when the plates 15 have been removed. To move the wedges 28 into locking position the operator will force the rods 29 downward. A reverse movement will retract the wedges 28 from locking position so that when the rod 25 is turned in the appropriate direction the lower ends of the wedge members 21, 22 will respond to the leverage exerted against them and be moved into form-contracting positions.

In order that the wedge members 21, 22 may be suitably supported or suspended from the plates 15, said wedge members are provided adjacent the plates 15 with notches 31 in which may be removably seated latches formed by arms 32 pivoted at 33 on the upper faces of the plates 15 adjacent the orifices 20. Swinging the latches inward causes them to engage the notches so that the plates 15 will be free from the wedge members 21, 22 and can be readily removed therefrom after the wall section has been poured.

Fastened along one longitudinal margin of each of the wedge members 21 by screws 34, 35, or their equivalents, is a U-shaped form member 36, and fastened along one longitudinal margin of the wedge member 22 by screws 37, 38, or their equivalents, is a

U-shaped form member 39. The form members 36, 39 project on opposite sides of the wedge members 21, 22 and the other longitudinal margins of said form members are 5 provided with slots 40 through which the screws 35, 38 project, the heads of the screws 35, 38 holding the adjacent portions of the form members 39, 36 against movement of said form members away from the wedge 10 members while permitting such movement as will allow expansion and contraction of said form members when the wedge members 21, 22 are shifted in the appropriate direction to produce such expansion and contraction 15 as above explained. When the wedge members 21, 22 are moved into their expanded position, as in Fig. 3, the form members 36, 39, as is readily understood, will be moved endwise from one another and will 20 be expanded sidewise also. When the wedge members 21, 22 are moved into their contracted positions shown in Fig. 4 the form members 36, 39 will be moved endwise toward one another and will be contracted 25 sidewise also. These form members 36, 39 are made of sheet metal of sufficiently light gage so that the expanding and contracting movement can be given them by turning of the rods 24, and the gage is sufficiently heavy 30 so as to withstand the pressure of cement or concrete thereagainst while the wall is being poured.

In order that the successively poured sections of the wall may be joined together 35 by waterproof joints, the under faces of the plates 15 are each provided with a groove-forming member 41 which may be half round in cross section and fastened by nails 42, or their equivalents, to the plates 40 15. These groove-forming members 41 extend beyond the longitudinal edges of the plates 15, and when the form members 36, 39 are in their expanded positions the groove-forming members 41 extend around 45 the upper ends of said form members and are spaced therefrom.

To prevent cement or concrete from passing into the space inside of the form members 36, 39, the under faces of the plates 15 are provided with caps 43 which are flanged at 44 to fit over and around the upper ends of the form members 36, 39. It is clear that when the parts above described are in 50 the positions shown in Fig. 5 of the drawings that the space between the form members 36, 39 and the plates 3 can readily be filled with cement or concrete by pouring the same into the space between the uppermost horizontal members 2 on both of the plates 15.

In practice, to construct a wall by the use of my invention, the lowermost pair or pairs of the horizontal members 2 will first 65 be laid on the footing or foundation, not

shown, previously prepared to receive the wall, then the corner standards 1 will be erected and a second pair or pairs of the horizontal members 2 will be fastened to the standards 1 and spaced sufficiently far from 70 the lowermost horizontal members 2 so that the form plates 3 can be readily fitted into place. Form plates 3 to the requisite number will then be slipped into place and fastened by engaging the latches 5 with the 75 grooves 4.

Then the wedge members 21, 22 after being moved to form-expanding positions as above described, with their expanded form members 36, 39 together with the plates 15, 80 which have been previously latched in place around the wedge members 21, 22, will be lowered into place so that the form members 36, 39 will occupy the middle portion 85 of the space between the opposing form plates 3 and so that the plates 15 will rest on the uppermost horizontal members 2. Then the pins 17 will be inserted in the appropriate holes 16, 19.

Then the wires 9 will be threaded through 90 the perforations 10 and secured to the washers 12 and the wedges 14 will be driven into place to draw the wires taut.

The cement or concrete for forming the wall will then be poured around the form 95 members 36, 39 so as to fill the space between said form members and the plates 3 and said concrete may be tamped into place in the usual manner of manufacturing concrete walls. This completes the lower- 100 most section of the wall and when this series of operations is finished a third pair of horizontal members 2 will be fastened to the standards 1 and the requisite number of plates 3 will be placed in position between 105 the second and third pairs of horizontal members preparatory to pouring the second section of the wall. By the time the form plates 3 of the second section of the wall are in place the concrete of the first 110 section has set sufficiently so that the inner forms are no longer required in the first section and they may be raised to position for pouring the second section of the wall.

In order that the inner forms may be raised, 115 the latches 32 will first be retracted from the notches 31 and the plates 15 will be raised off of the upper ends of the wedge members 21, 22. Then the operator will grasp the upper ends of the rods 29 and 120 pull on the same to retract the wedges 28 from their locking positions. Then the handles 26 will be turned in the appropriate direction to move the wedge members 21, 22 into their contracted positions so as 125 to contract the form members 36, 39 as hereinbefore explained. Contraction of the form members 36, 39 moves them away from the walls of the holes or chambers *a* which have been formed in the lower section of the 130

wall. The operator will then raise the wedge members 21, 22 and with them the form members 36, 39 to position immediately above their former positions. All of these inner forms when raised will then be expanded and the plates 15 applied in place and seated on the third set of horizontal members 2 the same as before described for the placing of the inner forms for forming 10 the lower section of the wall. Then the second section of the wall will be poured the same as the first section and the concrete will enter the grooves 45 formed by the groove-forming members 41 so as to make a 15 waterproof joint between the lowermost section and second section of the wall.

When the second section of the wall has been completed, the form plates 3 used in constructing the lower section of the wall 20 will be removed and are then used on the third section and the inner forms will be raised as described above so that the third section of the wall can be poured. Successive sections of the wall will thus be poured 25 until it is as high as desired, whereupon all of the forms may be removed so as to leave the completed wall with nothing but the wires 9 remaining therein.

From time to time, as the various sections 30 of the wall are completed, the chambers *a* will be filled with water so that the concrete will be properly cured throughout, and this can be readily accomplished because of the water-tight joints between the 35 successively poured sections. When the wall is wetted externally only it is generally not properly cured in its middle portions and therefore my construction insures against improper curing.

40 From the foregoing description it is clear that a hollow walled structure of concrete can be readily built and that the inner forms for producing the chambers in the walls can be quickly expanded for the pouring operation and can then as quickly be contracted and withdrawn from the poured section and raised into new positions and expanded for a repetition of the pouring operation.

It is understood that the invention is not 50 limited to the exact construction described above and shown in the drawings but that whatever changes and modifications are implied in the appended claims are included as being within the spirit and scope of the 55 claims.

I claim:

1. In combination, wedges having longitudinal grooves, U-shaped form members each fastened at one longitudinal margin to 60 one of the wedges and each shiftably fastened at its other margin to the other wedge.
2. In combination, wedge members having opposed inclined faces, U-shaped form mem-

bers each fastened at one longitudinal margin to the outer face of one of the wedge members and each member shiftably fastened at its other margin to the outer face of the other wedge member, and means to move the wedge members laterally to expand and contract the form members.

70 3. In combination, wedge members having opposed inclined faces and having longitudinal grooves in their opposed faces, a rod having its longitudinal edges inserted in the grooves so that turning of the rod 75 about its longitudinal axis will shift the wedge members, and U-shaped form members each fastened at one longitudinal margin to the outer face of one of the wedge members and each member shiftably fastened at its other margin to the outer face of the other wedge member.

4. In combination, a plate having an orifice, wedge members extending through the orifice and locked against relative lateral movement by the walls of the orifice, form members secured to the wedge members respectively so as to be moved toward and from one another by relative lateral movement of the wedge members, and means to produce relative lateral movement of the wedge members.

5. In combination, a plate having an orifice, wedge members extending through the orifice and locked against relative lateral 95 movement by the walls of the orifice, form members secured to the wedge members respectively so as to be moved toward and from one another by relative lateral movement of the wedge members, means to produce relative lateral movement of the wedge members, and means near one end of the wedge members to hold said members in expanded positions against the action of the 100 last named means.

105 6. In combination, a plate having an orifice, wedge members extending through the orifice, form members secured to the members respectively so as to be moved toward and from one another by relative lateral 110 movement of the wedge members, means to produce relative lateral movement of the wedge members, an ear fastened to one wedge member and extending past the joint between the wedge members, a wedge 115 adapted to be inserted between the ear and the adjacent wedge member, and an operating rod attached to the wedge to move it into and out of latching position.

120 Signed at Los Angeles, California, this 31st day of August, 1918.
